UNITED STATES PATENT OFFICE.

HARVEY HUBBELL, OF BRIDGEPORT, CONNECTICUT.

FLUSH-ATTACHMENT-PLUG RECEPTACLE.

SPECIFICATION forming part of Letters Patent No. 793,197, dated June 27, 1905.

Application filed February 25, 1905. Serial No. 247,303.

To all whom it may concern:

Be it known that I, HARVEY HUBBELL, a citizen of the United States, residing at Bridgeport, county of Fairfield, State of Connecticut, have invented a new and useful Flush-Attachment-Plug Receptacle, of which the following is a specification.

My invention has for its general object to produce a practical direct-acting flush-attachment-plug receptacle that will avoid the objections raised by the underwriters to receptacles of this type now upon the market and shall have for its special objects to produce a flush-attachment-plug receptacle that will provide ample current-carrying capacity, in which the possibility of arcing or sparking in making the contact shall be wholly done away with, in which there shall be no exposed terminals, which will do away with the necessity for a hinged cover or lid, will permit all electrical connections with the plug to be made from the front without removing the base or opening the wall-pocket, and which can under no circumstances be dangerous to the user.

With these and other objects in view I have devised the novel flush-attachment-plug receptacle, which I will now describe, referring to the accompanying drawings, forming a part of this specification, and using reference characters to indicate the several parts.

Figure 1 is an elevation of my novel flush-attachment-plug receptacle as in use, the cap being in place and a portion of the face-plate broken away to show the wall-pocket; Fig. 2, a longitudinal section of the receptacle complete and attached to a wall-pocket, the cap being in elevation; Fig. 3, a plan view of the receptacle detached, the cap being removed; Fig. 4, a similar view, the covering-block being removed; Fig. 5, a section of the base on the line 5 5 in Fig. 4; Fig. 6, a section of the covering-block on the line 6 6 in Fig. 3; Fig. 7, an elevation of the cap detached; Fig. 8, an inverted plan view of the covering-block detached; and Fig. 9 is an end view of one of the end plates detached, as from the bottom of the sheet in Fig. 3.

A denotes the base, and B the covering-

block, of my novel attachment-plug receptacle, both of which are preferably made of porcelain; C, the face-plate; D, the cap, and E a wall-pocket, which may be of any ordinary or preferred construction. The base is provided with a transverse recess 10, which receives the covering-block. The outer face of the covering-block in the assembled position lies substantially flush with the top of the base and is provided with a rosette 11, which projects through a central opening 12 in the face-plate, the top of the rosette lying substantially flush with the outer surface of the face-plate. In the base of recess 10 are recesses 13, in which the contact-plates 14 are secured.

15 denotes raised portions on the bottom of recess 10, and 16 depressions which interlock, respectively, with corresponding depressions 17 and raised portions 18 on the under side of covering-block B to retain the covering-block against lateral displacement on the base.

19 denotes recesses in the sides of the base through which the electrical connections may pass from the wall-pocket for attachment to the contact-plates by binding-screws 20. The covering-block is secured to the base by means of a center screw 21, the head of which lies in a recess 22 in the outer side of the covering-block and which passes through both covering-block and base and engages a nut 23 in a recess 24 in the back of the base. The base is attached to the wall-pocket by means of screws 25, which pass through slots 26 in end plates 27, which are secured to the base by means of screws 28. By providing two slots in each end plate I insure that the base may be attached to any ordinary wall-pocket and also that the base may be shifted slightly to place the face-plate in alinement with moldings or casings should the wall-pocket be set out of alinement. As it is required that the projecting attaching ends of the end plates be relatively thin and that they be made relatively heavy where they are attached to the base, so as to give ample strength where the strain comes in use, I have devised a special form of end plate made of relatively thin

sheet metal and doubled upon itself in order to give strength where it is required. (See Fig. 2 in connection with Figs. 3 and 9.) The end plates are rigidly locked against lateral movement by means of flanges 29, which are turned down into longitudinal grooves 30 in the face of the base at the ends.

31 denotes recesses in the under side of the face-plate, which receive the heads of screws 25, by which the base is attached to the wall-pocket. The face-plate is secured to the base by means of screws 32, which pass through from the front and engage the doubled portion of the end plates, recesses 33 being provided in the ends of the base to receive screws 28 and 32. The cap is shown as provided with knife-blade contacts 34, which are adapted to engage contacts 14. It should be noted, however, that the contact-plates, although they are secured to the base, lie in insulating-chambers 35 in the covering-block and that the knife-blade contacts can only engage the contact-plates in these chambers and after they have been passed through contracted insulating-passages 36, which lead from the face of the rosette into the insulating-chambers.

The operation of my novel attachment-plug receptacle is so simple as to hardly require explanation. The base is attached in place 30 in a wall-pocket by means of screws 25, which pass through the slots in the end plates. The electrical connections are passed through recesses 19 in the base and are connected to the binding-screws, and the covering-block is attached to the base by means of the center screw, the corresponding raised portions and depressions on the base and block acting to retain the covering-block firmly in place upon the base and prevent lateral movement. The 35 face-plate is then placed in position, the rosette extending through the central opening, and is secured in place by means of screws 32, which engage the end plates. Should it be required at any time to detach the electrical 40 connections, it can be done from the front without removing the base from the wall-pocket by simply removing the face-plate and covering-block. I thus dispense entirely with the use of a hinged cover or lid, which has 45 been found so objectionable in most of the attachment-plug receptacles now in use. In making an electrical connection with the receptacle the operator simply passes the knife-blade contacts upon the cap through the insulating-passages in the rosette and into engagement with the contact-plates in the insulating-chambers. The knife-blade contacts are shown as provided with recesses 37, which are engaged by locking-springs 38 in the insulating-chambers to retain the cap securely in engagement with the plug. To disengage the cap, it is of course necessary to pull upon it strongly enough to overcome the engagement of the locking-springs with the recesses 55

in the knife-blade contacts, the movement of 65 the cap being direct both in attaching and withdrawing.

Having thus described my invention, I claim—

1. In a flush-attachment-plug receptacle, 70 the combination with a base having a transverse recess and contact-plates extending upward from the bottom thereof, of a covering-block lying in said recess and having insulating-chambers receiving the contact-plates, 75 contracted insulating-passages leading into said insulating-chambers and a center screw passing through the covering-block and base whereby said parts are locked together.

2. In a flush-attachment-plug receptacle, 80 the combination with a base having a transverse recess, raised portions and depressed portions in the bottom thereof and contact-plates secured in said recess, of a covering-block lying in said recess and having raised 85 and depressed portions corresponding with the raised and depressed portions in the bottom of the recess, insulating-chambers which receive the contact-plates, contracted insulating-passages leading into the insulating-chambers 90 and a center screw whereby the base and covering-block are locked together, the corresponding recesses and depressions in the base and covering-block holding the latter against displacement. 95

3. In a flush-attachment-plug receptacle, the combination with a base having a transverse recess, contact-plates secured in said recess and end plates adapted for attachment to a wall-pocket, of a covering-block lying in the 100 recess and having insulating-chambers receiving the contact-plates and contracted insulating-passages leading into the insulating-chambers, a center screw whereby the covering-block is secured to the base and a face-plate 105 attached to the end plates and having a central opening through which the insulating-passages are exposed.

4. In a flush-attachment-plug receptacle, 110 the combination with a base having a transverse recess, and longitudinal grooves in its face at the ends, contact-plates secured in said recess and end plates secured to the base and having flanges turned down into the grooves, of a covering-block lying in the recess and 115 having insulating-chambers receiving the contact-plates and contracted insulating-passages leading into the insulating-chambers.

5. In a flush-attachment-plug receptacle, 120 the combination with a base having a transverse recess and longitudinal grooves in its face, contact-plates secured in said recess, end plates made of relatively thin metal so as to provide thin attaching ends and doubled upon themselves at the point of attachment to the base and having flanges turned down into the grooves in the base to retain them in place, and screws in the base by which the end plates are 125

secured thereto, of a covering-block secured in the recess and having insulating-chambers receiving the contact-plates and contracted insulating-passages leading into the insulating-chambers.

6. In a flush-attachment-plug receptacle, the combination with a base having a transverse recess, contact-plates secured in said recess and end plates having projecting ends 10 with slots to receive screws for attachment to a wall-pocket, of a covering-block lying in the recess and having insulating-chambers receiving the contact-plates and contracted insulating-passages leading into the insulating-chambers, and a face-plate attached to the end plates and having in its under side recesses to receive the screws which attach the base to a wall-pocket and a central opening through which the insulating-passages are exposed.
- 15 7. In a flush-attachment-plug receptacle,

the combination with a base having a transverse recess and contact-plates and locking-springs secured in said recess, of a covering-block lying in the recess and having insulating-chambers receiving the contact-plates and contracted insulating-passages leading into the insulating-chambers, a face-plate adapted for attachment to the base and having a central opening through which the insulating-passages are exposed and a cap having knife-blade contacts passing through the insulating-passages and engaging the contact-plates and locking-springs in the insulating-chambers.

In testimony whereof I affix my signature in presence of two witnesses.

HARVEY HUBBELL.
